INVENTOR

Earl M. Miller,

John J. Hennigan
ATTORNEY

UNITED STATES PATENT OFFICE.

EARL M. MILLER, OF ELIZABETHTOWN, PENNSYLVANIA.

ELECTRIC SIGN.

1,301,586.

Specification of Letters Patent. Patented Apr. 22, 1919.

Application filed April 3, 1918. Serial No. 226,539.

To all whom it may concern:

Be it known that I, EARL M. MILLER, a citizen of the United States, residing at Elizabethtown, in the county of Lancaster and State of Pennsylvania, have invented certain new and useful Improvements in Electric Signs, of which the following is a specification, reference being had therein to the accompanying drawing.

10 This invention relates to an electric sign of that class in which the letters or figures are interchangeable, so that the wording of the sign may be changed as desired.

15 In the present signs for this purpose the letters or figures have electric bulbs mounted thereon and to remove and change the letters, the electric wiring has to be changed or adjusted.

20 Also in handling the letters or figures the bulbs are liable to become broken, and further there are a great many bulbs to be renewed from time to time.

25 The object of the present invention is to provide an electric sign in which the letters or figures are perforated, and which are illuminated by reflected light from a few powerful bulbs which are mounted within the sign and fully protected.

30 Another object of the invention is to provide a sign that shall be simple, durable and cheap.

35 With these and other objects in view my invention consists in certain constructions and combination of parts as will be fully described and claimed in the annexed specification, and which are illustrated in the accompanying drawings which form a part of this application, and in which like figures of reference refer to corresponding parts in 40 all of the views, but it is fully understood that while I have described my invention as shown that I do not confine myself to the exact design as shown as slight changes may be made in the construction and combination of the several parts, without departing from the spirit of the invention.

45 In the drawings:—

Figure 1. is a front elevation of a sign embodying my invention.

50 Fig. 2. is an end view of the same.

Fig. 3. is a sectional view taken on the line X—X of Fig. 2.

Fig. 4. is a sectional view taken on the line Y—Y of Fig. 1. and showing the 55 method of removing the letters.

Fig. 5. is a back view of one of the figures.

Fig. 6. is a cross sectional view of one of the figures.

Referring to the drawings, the sign comprises a rectangular box 1, formed with a slanting back 2, to form a reflector for the lighting bulbs 3, which are mounted in the top, and supplied with the current wires 4.

The front 5, of the box 1, is formed with a flanged frame 6, surrounding the opening, and forming a groove 7, within which the plates 8 are retained.

Referring to Figs. 5 and 6, the letters, figures, or other characters 9 are carried by plates 8, each plate having a cut out portion of the form of the letter or figure and to which the letter or figure is secured; said letter or figure having the perforations 10.

The top, bottom, and one side of said letter plate 8 are provided with tongues 11 forming side edges for entering the grooves 7, and the other side edge of said plate is provided with a flanged strip 12, forming a groove 13 for the reception of the tongue of the next letter or figure plate. By the use of blank plates 14, of different widths, the opening may be filled.

The upper groove 7 is of sufficient depth to allow the plates to be raised until the lower tongues clear the bottom groove. The plates 15 are then sprung outward at the bottom and removed from the upper groove, as shown in Fig. 6.

As the upper groove 7, in said opening is deeper than the bottom groove; to remove 90 the plates, they are raised until the lower edge can be removed from the bottom groove, and the plates are sprung outward at the bottom and removed from the upper groove as shown in Fig. 6. 95

It is understood that the sign may be of any shape or size desired, and contain as many letters or figures as required.

Having thus described my invention, what I claim as new and desire to secure by Letters Patent, is:—

1. In a sign, the combination with a box-shaped frame provided with an opening, illuminating means adapted to project the light outwardly toward said opening, perforated character plates, and means to retain the plates in said opening, a plurality of said plates each provided with a groove along one side edge adapted to be engaged by the side edge of an adjacent plate. 105

2. In a sign, the combination with a box-shaped frame provided with an opening,

illuminating means adapted to project the light outwardly toward said opening, and perforated character plates retainable in grooves in the upper and lower edges of said opening, a plurality of said plates each provided with a groove along one side edge adapted to be engaged by the side edge of an adjacent plate, whereby each plate may be engaged with the frame and with the adjacent plate or plates.

3. In a sign, the combination with a box-shaped frame provided with an opening and means forming grooves along the upper and lower edges of the opening, illuminating means adapted to project the light outwardly toward said opening, and perforated

character plates the upper and lower edges of which are adapted to engage said grooves, one of said grooves being of sufficient depth to allow the plates to be moved vertically 20 until they clear the other groove, a plurality of said plates each provided with a groove along one side edge adapted to be engaged by the side edge of an adjacent plate.

25

In testimony whereof I affix my signature in presence of two witnesses.

EARL M. MILLER.

Witnesses:

SUMNER V. HOSTERMAN,
WM. F. LEBZELTER.
